US00D757009S

(12) **United States Design Patent**
Oberpriller et al.

(10) **Patent No.:** **US D757,009 S**
(b4) **Date of Patent:** **** May 24, 2016**

(54) **IN-COUNTER BARCODE SCANNER**(71) Applicant: **Hand Held Products, Inc.**, Fort Mill, SC (US)(72) Inventors: **Mark Lee Oberpriller**, Atlanta, GA (US); **Timothy R. Fitch**, Syracuse, NY (US)(73) Assignee: **Hand Held Products, Inc.**, Fort Mill, SC (US)(**) Term: **15 Years**(21) Appl. No.: **29/528,165**(22) Filed: **May 27, 2015****Related U.S. Application Data**

(63) Continuation of application No. 29/494,725, filed on Jun. 24, 2014, now Pat. No. Des. 730,901.

(51) **LOC (10) Cl.** ..... **14-02**(52) **U.S. Cl.**USPC ..... **D14/420; D14/421**(58) **Field of Classification Search**

CLAIM

The ornamental design for an in-counter barcode scanner, as shown and described.

DESCRIPTION

FIG. 1 is a perspective view of an in-counter barcode scanner; FIG. 2 is another perspective view of the in-counter barcode scanner;

FIG. 3 is a front elevation view of the in-counter barcode scanner;

FIG. 4 is a rear elevation view of the in-counter barcode scanner;

FIG. 5 is a right side elevation view of the in-counter barcode scanner;

FIG. 6 is a left side elevation view of the in-counter barcode scanner;
